(57) **CLAIM**

The ornamental design for a litter box, as shown and described.

DESCRIPTION

FIG. 1 is a front, right, and top perspective view of a litter box, showing my new design;

FIG. 2 is a rear, left, and bottom perspective view of the litter box in FIG. 1;

FIG. 3 is a front elevation view thereof;

FIG. 4 is a rear elevation view thereof;

FIG. 5 is a left side elevation view thereof;

FIG. 6 is a right side elevation plan view thereof;

FIG. 7 is a top plan view thereof;

FIG. 8 is a bottom plan view thereof; and,

FIG. 9 is an enlarged view of an encircled area labeled “9” in FIG. 1.

The broken lines shown in the drawings are included for the purpose of illustrating portions of the litter box that form no part of the claimed design.

Dot-dash broken lines in FIGS. 1 and 9 framing portions of the claimed design that are illustrated for enlargements form no part of the claimed design.

1 Claim, 9 Drawing Sheets(56)
